CLAIM

The ornamental design for a key fob for a magnetic key lock, as shown.

DESCRIPTION

FIG. 1 illustrates a front perspective view of a key fob;

FIG. 2 illustrates a front view of the key fob;

FIG. 3 illustrates a rear view of the key fob;

FIG. 4 illustrates a left side view of the key fob;

FIG. 5 illustrates a top view of the key fob; and,

FIG. 6 illustrates a right side view of the key fob.

The broken lines in FIGS. 1, 2, 4 and 6 are included for the purpose of illustrating environmental matter and form no part of the claimed design.
